Primary Examiner — Lucy Lieberman(74) *Attorney, Agent, or Firm* — Fleit Gibbons Gutman Bongini & Bianco PL; Martin Fleit; Paul D. Bianco(57) **CLAIM**

The ornamental design for a data recording terminal, as shown and described.

DESCRIPTION

FIG. 1 is a perspective view of a data recording terminal according to the invention; and,

FIG. 2 is a front view of the data recording terminal of FIG. 1. The text shown in broken lines on the display of the data recording terminal is for illustrative purposes only and forms no part of the claimed design.
